UNITED STATES PATENT OFFICE.

FRANK PFOUS, OF COSHOCOTON, OHIO, ASSIGNOR TO THE H. D. BEACH COMPANY, OF COSHOCOTON, OHIO, A CORPORATION OF OHIO.

DESIGN FOR A ROCKING SAFETY-MATCH HOLDER.

Application filed December 1, 1922. Serial No. 4,456. Term of patent 7 years.

To all whom it may concern:

Be it known that I, FRANK PFOUS, a citizen of the United States, residing at Coshocton, in the county of Coshocton and State of Ohio, have invented a new, original, and ornamental Design for a Rocking Safety-Match Holder, of which the following is a specification.

Referring to the drawing—

The figure is a perspective view of a design for a rocking safety match holder.

I claim—

The ornamental design for a rocking safety match holder, substantially as shown.

In testimony, that I claim the foregoing as my own, I have hereto affixed my signature.

FRANK PFOUS.
